UNITED STATES PATENT OFFICE.

FRANK H. DOTY, OF TROY, NEW YORK, ASSIGNOR TO WILLIAM BARKER COMPANY, OF WATERVLIET, NEW YORK, A CORPORATION OF NEW YORK.

SOFT FOLD-COLLAR.

1,283,698.

Specification of Letters Patent. Patented Nov. 5, 1918.

Application filed February 25, 1918. Serial No. 218,940.

To all whom it may concern:

Be it known that I, FRANK H. Doty, a citizen of the United States, residing at Troy, county of Rensselaer, and State of New York, have invented certain new and useful Improvements in Soft Fold-Collars, of which the following is a specification.

Reference may be had to the accompanying drawings, and the reference characters 10 marked thereon, which form a part of this specification. Similar characters refer to similar parts in the several figures therein.

This invention relates to various kinds of collars having certain run-and-stitched members which are to be worn soft or not stiffly starched.

The principal object of the invention is to utilize certain structural features characteristic of such a run-and-stitched collar member to accommodate a separate stiffening member, whereby said collar member is supported and held in proper position in use.

Other objects will appear in connection with the following description.

25 Figure 1 of the drawings is a view in perspective of a soft fold-collar embodying my invention.

Fig. 2 is a cross-section of one end of the folded-over top of the collar taken on the 30 broken line 2—2 in Fig. 1.

Fig. 3 is a similar section showing the three plies of the top run together.

Fig. 4 is a similar view showing the run-together plies turned inside out.

35 Fig. 5 is a similar view showing the run-and-turned plies stitched together.

Fig. 6 is a view in perspective of the separate stiffening member.

Referring to the drawings wherein the invention is shown in preferred form, 1 represents the band, and 2 the folded-over top of the collar, the band being shown provided with the usual buttonholes, 3.

45 The top of the collar which is run, turned and stitched in the usual manner of making a hand-turned collar, may be formed of any desired plural number of plies of fabric.

I have shown the top formed of an inner facing-ply, 4, an outer facing-ply, 5, and an 50 interlining ply, 6, of fabric. In making the top of the collar, these plies are superimposed one upon another with one of the facing-plies and the interlining ply outermost, and the other facing-ply therebetween, in

which position they are run together by a 55 seam, 7, as shown in Fig. 3.

The run-together plies are then turned inside out between the two facing-plies, 4 and 5, by which the run-seam 7, is concealed, as shown in Fig. 4.

60 The run-and-turned plies are then stitched together as at 8 along a line substantially parallel with, and at a substantial distance from, the edge of the run-and-turned plies, as shown in Fig. 5, and also in Fig. 1.

65 This manner of making a collar forms a space or pocket, 9, between the plies and extending along the edge-portion of the collar between the two lines of stitching, 7 and 8, which pocket as such, has heretofore had 70 no utility and performed no function.

In carrying out my invention, I employ this pocket, 9, where it extends along the ends of the folded-over top to accommodate a separate stiffening member or strip, 10, 75 which supports and holds in proper position the end of the top in use.

This stiffening strip or member may be made of any suitable material having the desired degree of stiffness such as celluloid, 80 metal, whalebone, featherbone, or the like.

By utilizing the pocket, 9, I am able to properly support the stiffening member, 10, which in turn properly supports the end of the folded-over top; and I am able to accomplish this result without increasing the cost of producing the collar, except for the cost of the stiffening member itself, as no additional time or operation is required to produce the pocket which receives the stiffening member.

85 When the top has been run, turned and stitched in the usual manner, the stiffening members are pushed into the respective pockets, 9, through the open side of the top 95 which open side is then inserted and stitched within the band in the usual manner, thus closing the pockets at the unturned edge of the folded-over top.

I prefer to have the pocket thus closed, although this is not an essential feature of my invention.

100 While I have shown and described my invention as applied to the end of the folded-over top, it will be understood that it is also 105 applicable to any run-and-stitched portion of the collar into which it is desired to incorporate a separate stiffening member.

What I claim as new and desire to secure by Letters Patent is:

1. A collar having a member formed of a plurality of plies run, turned and stitched whereby a pocket is formed between the plies, and between the two lines of stitching whereby the member is run and stitched; and having inserted in said pocket a separate stiffening member.
- 10 2. A collar having a band and a soft folded-over top, said folded-over top being formed

of a plurality of plies run, turned and stitched whereby a pocket is formed along an end of the folded-over top between the plies, and between the two lines of stitching whereby the folded-over top is run, and stitched; and having inserted in said pocket a separate stiffening member. 15

In testimony whereof, I have hereunto set my hand this 21st day of February, 1918.

FRANK H. DOTY.
